(57) **CLAIM**

The ornamental design for a portion of a jewelry item, as shown and described.

DESCRIPTION

FIG. 1 is right front top perspective view of a portion of a jewelry item showing my new design in a first embodiment.

FIG. 2 is a left rear top perspective view thereof.

FIG. 3 is a left rear bottom perspective view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a top plan view thereof.

FIG. 9 is a bottom plan view thereof.

FIG. 10 is right front top perspective view of a portion of a jewelry item showing my new design in a second embodiment.

FIG. 11 is a left rear top perspective view thereof.

FIG. 12 is a left rear bottom perspective view thereof.

FIG. 13 is a front elevation view thereof.

FIG. 14 is a rear elevation view thereof.

FIG. 15 is a right side elevation view thereof.

FIG. 16 is a left side elevation view thereof.

FIG. 17 is a top plan view thereof; and,

FIG. 18 is a bottom plan view thereof.

In the second embodiment the support openings form no part of the claimed design. The dash-dash lines represent portions of the portion of a jewelry item that form no part of the claimed design. The dash-dot-dash lining indicates the bounds of the claimed design and form no part thereof.

1 Claim, 14 Drawing Sheets
